UNITED STATES PATENT OFFICE.

CHARLES H. CROSSETTE, OF CHICAGO, ILLINOIS.

DESIGN FOR A NECKSCARF.

SPECIFICATION forming part of Design No. 11,739, dated April 20, 1880.

Application filed February 26, 1880. Term of patent 3½ years.

To all whom it may concern:

Be it known that I, CHARLES H. CROSSETTE, a citizen of the United States, residing at Chicago, in the county of Cook and State of Illinois, have invented and produced a new and original Design for Neckscarfs, of which the following is a specification, reference being had to the accompanying drawing, forming a part thereof.

- 10 The drawing represents a front view of my new and original design neckscarf.

Heretofore neckscarfs consisting of a center-piece and crossed aprons have had the outer side edges of said aprons straight or angular, 15 or else elliptically curved from their top toward their bottom, said curves terminating in straight edges near the bottom, and their inner edges straight or angular.

The leading feature of my design consists in 20 the curved outer and inner edges of the crossed aprons, which are reverse on each side of said aprons and terminate in each other, giving the aprons, when crossed, an appearance resembling a figure 8 open at the top 25 and bottom, said openings being closed by center-pieces, so that the scarf presents the same appearance upon the wearer when either end is up, and is thus made reversible.

A represents a neckband, B B' center-pieces, 30 and C C' crossed aprons, secured together in the usual manner to form a flat neckscarf. The inner edges of the aprons C C' are respectively concavely curved from a to b, the curve upon one edge of a single apron being a reverse 35 curve to the one upon its opposite edge—that is to say, they are as to each other concave and convex, but as inner edges of the scarf concave. At b the inner edges terminate in con-

vex edges, which extend upon the outer edges of the scarf from b to c, from whence they 40 merge into and are joined to the concave inner edges by the short convexly-curved edges upon the ends of the aprons between c and a.

It will be observed that the outer edges of the aprons upon one side of the scarf are formed 45 of two curves having the same direction, but meeting at the center of length of said scarf, and that the outer edges upon the opposite side correspond with them in this respect, but curve in opposite directions, the inner edge 50 of each apron corresponding with its respective outer edge—i. e., parallel to it—and thereby giving the edges of the crossed aprons the general appearance of the outline of both the inner and outer edges of a figure 8 having its 55 ends truncated, the center-pieces B B' closing the space between the points of intersection of the inner edges and the ends of the crossed aprons, causing the scarf to present the same appearance, whether it be in the position 60 shown in the drawing or turned end for end.

Having thus described my design, what I claim, and desire to secure by Letters Patent, is—

The design for a neckscarf, the same consisting of the crossed aprons provided with concave inner edges parallel with and terminating in convex outer edges, said aprons presenting in outline the appearance of a figure 8 having its ends truncated, substantially as 65 described, and shown in the accompanying drawing.

CHARLES H. CROSSETTE.
